UNITED STATES PATENT OFFICE.

CARL WILLIAM GRAY, OF LANKERSHIM, MARY JONES BURDICK, OF ALHAMBRA, MILO STUART MOORE, OF LOS ANGELES, AND CLAUDE W. SANDIFUR, OF LANKERSHIM, CALIFORNIA.

DESIGN FOR A LABORATORY CHEMISTRY TABLE.

Application filed March 2, 1927. Serial No. 20,947. Term of patent 14 years.

To all whom it may concern:

Be it known that we, CARL WILLIAM GRAY, MARY JONES BURDICK, MILO STUART MOORE, and CLAUDE W. SANDIFUR, citizens of the United States, residing, respectively, at Lankershim, Alhambra, Los Angeles, and Lankershim, all in the county of Los Angeles and State of California, have invented a new, original, and ornamental Design for a Laboratory Chemistry Table, of which the following is a specification, reference being had to the accompanying drawing, forming a part thereof.

The figure is a perspective view of a lab-

oratory chemistry table showing our new design.

We claim:

The ornamental design for a laboratory chemistry table as shown.

Signed at Los Angeles, in the county of Los Angeles and State of California, this 21st day of December, 1926.

CARL WILLIAM GRAY.
MARY JONES BURDICK.
MILO STUART MOORE.
CLAUDE W. SANDIFUR.
